UNITED STATES PATENT OFFICE.

JOSEPH C. DONNELLY, OF BARBERTON, OHIO, ASSIGNOR TO THE DIAMOND MATCH COMPANY, OF CHICAGO, ILLINOIS, A CORPORATION OF ILLINOIS.

MATCH-MACHINE.

1,236,687.

Specification of Letters Patent. Patented Aug. 14, 1917.

Application filed November 24, 1915. Serial No. 63,190.

To all whom it may concern:

Be it known that I, JOSEPH C. DONNELLY, a citizen of the United States, and resident of Barberton, in the county of Summit and 5 State of Ohio, have invented certain new and useful Improvements in Match-Machines, of which the following is a specification.

This invention relates to that class of 10 match machines in which is employed an endless carrier by means of which splints, in separated rows, are transported through the match making path, including a paraffin applying station and a head-composition 15 applying station or stations.

The object of my invention is to provide for such machines a mechanism of simple and efficient construction and operation whereby the parts of the splint carrier located 20 immediately above the paraffin and composition applying stations can be positively and rapidly lifted out of action and at the same time the machine can be stopped, (although the composition-applying roller 25 continues to rotate as usual) thereby obviating any liability of the carrier, with its depending splints, overrunning the respective stations when the machine is being thrown out of operation.

30 In the present illustrative form of embodiment of my invention, I employ raising and lowering mechanism for the carrier and brake means for the main shaft of the match machine, together with devices which can be actuated with facility and rapidity to throw off the power from the main shaft, apply the brake means to the shaft, and at the same time actuate the said mechanism to raise a part or parts of the carrier and lift 35 the splints from the paraffin and composition applying paths.

The invention comprises novel features of construction and combinations of parts which will be hereinafter described and 40 claimed.

In the drawings—

Figure 1 is a side elevation of a part of a match machine embodying a form of my invention; the splint carrier being shown in 45 up position.

Fig. 2 is a plan, partly in section, of the pneumatic structure, the motor, the power

shaft of the match machine, and associated mechanisms.

Fig. 3 is an end elevation of the pneumatic structure, and adjuncts.

Fig. 4 is a sectional elevation thereof.

Fig. 5 is a view of a part of the brake wheel, the brake lever, and adjuncts.

Fig. 6 is a section of the power driven shaft and the sprocket wheel thereon with which the main shaft of the match machine is geared, showing the band clutch for said wheel.

Fig. 7 is a transverse vertical section 65 through the paraffin chest and the chain supporting and lifting frame, as on the line 7—7 of Fig. 1.

Fig. 8 is a similar section, through the chain supporting and lifting frame, and 70 associated parts, adjacent the composition chest, as on line 8—8 of Fig. 1.

Referring to the drawings, 10 designates a part of the endless splint-carrier chain of a continuous match machine, which chain, 75 in the form illustrated, comprises a series of perforated plates linked together at their edges, and provided with marginal gear racks 11 throughout the length of the chain. This chain is suitably supported and guided 80 throughout its circuit, and pairs of spaced power-driven gear wheels are arranged at intervals in the circuit so as to mesh with the gear racks and impel the chain; said wheels being appropriately geared with and 85 driven from the main shaft 12 of the match machine as illustrated, for example, in U. S. Patent No. 528,457, dated October 30, 1894.

A pair of these gear wheels is indicated at 13, their shaft 14 bearing at one end a 90 sprocket wheel 15 which is operatively connected through suitable gearing with the main shaft. As such gearing is fully set out in the patent referred to it is deemed unnecessary herein to show or describe it in 95 detail.

Splints are inserted into the successive rows of perforations of the chain plates at the front or receiving end of the machine, and are thereby transported through the 100 match making path, in which are included the paraffin containing tank 16 with the contents of which the traveling splints are treated, and one or more composition apply-

ing structures, of which one is illustrated at 17, by means of which the composition for the ignitable bulbs or "heads" is applied to the free ends of the splints after they leave the paraffin bath.

18 designates a power-driven shaft having its bearings in suitable standards in rear of the main shaft of the match machine. This shaft 18 is continuously driven from a convenient source of power, as, for example, an electric motor 19, the shaft of which is operatively connected with the shaft 18 through meshing gear wheels 20, 21 on the respective shafts.

15 On the shaft 18 is loosely mounted a sprocket wheel 22 which is geared by means of a chain 23 with a similar wheel 24 on the main shaft of the match machine, a suitable clutch being provided to lock or unlock the wheel 22 to or from the shaft 18 as desired. In the present instance an ordinary band clutch is employed, the same comprising a band 25 which, encircling a hub 26 on the sprocket wheel, is connected at its ends to the pivot pin of a tension arm 27 on the wheel, the free end of which arm depends into the path of a sliding clutch cone 28 on the shaft 18. When the cone is moved toward the wheel 22 the tension arm is raised in a manner to tighten the band on the hub and thus clutch the sprocket wheel to the shaft 18, and when the cone is retracted the tension arm is released and the wheel 22 is thus unclutched from the shaft 18. The cone is pivotally connected to the arm 29 of a shipper lever 30 fulcrumed on a suitably-disposed standard 31. The means for actuating this lever will hereinafter appear.

32 designates a brake wheel preferably affixed directly to the main shaft of the match machine, and 33 a brake shoe positioned adjacent the periphery of the wheel. This shoe comprises a block of appropriate material seated in a socket in a lever 34 which is fulcrumed in a suitably-disposed bracket 35. The outer portion of the lever has formed therein a cam slot 36 into which projects a roller on the lower end of a depending lever 37 carried by a rock-shaft 38 having its bearings in uprights 39. This lever is connected by means of a link 40 with one arm 41 of the shipper lever above referred to, which lever is connected to the rod 42 of a pneumatically controlled piston head 43 working in a cylinder 44 on a standard 45. This cylinder is provided at or near its respective ends with ports 46 through which compressed air from a supply port 47 is admitted to either end of the cylinder in order to shift the piston from one end to the other of the cylinder as desired. In the present instance an ordinary Corliss valve 48 is mounted and arranged to control the admission of air to the respective ports of the cylinder, the stem of said valve being pro-

vided with an exterior arm 49 to which is connected a hand-lever 50. This lever is provided with a socketed locking loop 51 either of the sockets of which may be engaged with a pin 52 on an arm 53' projecting from the adjacent standard 39 when the lever 50 is shifted to position the valve for admission of air to the desired end of the cylinder.

When the compressed air is admitted to one end of the cylinder the piston is instantly actuated to pull the attached arm of the shipper lever 30, which lever thereupon retracts the cone 28 and releases the clutch band on the hub of the sprocket wheel 22, and at the same time said lever operates the rock-lever 37 in a manner to raise the brake lever and apply the brake block effectively to the opposing brake wheel on the main shaft. Simultaneously with the performance of these functions, the shipper lever effects through appropriate connections hereinafter described the raising of movable chain supporting structures 53, 54 directly above the paraffin tank and the composition chest respectively. These structures may be of any usual or approved construction. In the present instance the structure 53 comprises a pair of spaced bridge rails 55 carried by a supporting frame 56 which is hinged at one end to brackets 57 on the adjacent frame posts of the match machine so as to over-hang the paraffin tank and maintain the rails in position to support and guide the marginal edges of the carrier chain during its traverse above the tank. By raising or lowering this structure 53 the portion of the splint chain supported on the bridge rails may be correspondingly moved, so as to raise the splints from or lower them into the paraffin bath. The structure 54 comprises spaced bridge rails 58 carried by a supporting frame 59 which is hinged at one end on the transverse shaft 14 carrying the pair of chain-driving gear wheels 13 above referred to. The opposite end of this frame carries a hexagonal drum 60 about which the splint chain is flexed in its travel. On the sides of the frame 59 are laterally-projecting anti-friction rollers 61 against which bear sector cams 62 carried by a rock-shaft 63 having its bearings in brackets on the frame 64 of the composition structure, whereby when the shaft 63 is properly actuated, the hinged structure 54, with the proximate portion of the splint chain, may be raised or lowered to move the splints from or into the path of the usual composition roller 65, as desired.

The connections between the pneumatically-actuated piston and the structures 53, 54 are preferably of the following description: 66 designates a bell-crank lever pivoted to a bracket 67 on a frame post 68 adjacent the outer end of the shipper lever. This end

of the shipper lever is connected by means of a link 69 with the depending arm of the bell-crank lever 66, the other arm of the latter being connected by means of a link 70 with a crank-arm 71 on an elevated rocker-shaft 72 which, extending from side to side of the machine, has its bearings in appropriate brackets on the frame posts. By this construction motion is transmitted from the 10 shipper-lever to the rocker-shaft 72.

73, 74 designate two rocker-shafts arranged above the structures 53, 54 respectively; said shafts being parallel to the rocker-shaft 72 and being similarly mounted 15 in brackets on appropriate frame-posts. The shaft 73 is provided about midway between its ends with a crank arm 75, which is connected by means of a link 77 with a bracket 78 on a cross-rod of the structure 53.

20 The shaft 74 is provided at its respective ends with crank arms 76 being connected by links 79 with crank-arms 80 on the cam shaft 63. The rocker-shafts 72, 73, 74 are provided at their ends with parallel levers 81, 25 82, 83, respectively; the lower arms of which on each side of the machine are connected by a rod 84 and the upper arms are connected by a rod 85. Consequently when the rocker-shaft 72 is actuated by movement of 30 the shipper lever the remaining shafts 73, 74 are correspondingly moved; thus effecting through the appropriate crank and link connections the raising or lowering of the structures 53, 54, as above described; that

35 is to say, when air is admitted to the cylinder to operate the piston to stop the machine, the power is thrown off from the main shaft, the brake is applied and the two chain supporting structures are raised; and when air 40 is admitted to the cylinder to operate the piston to start the machine, the power is applied to the main shaft, the brake is released and the two supporting structures are lowered.

45 The composition applying mechanism is (or may be) of usual construction, that is to say, it includes a vat within which are rotatably mounted a composition mixer and the composition-applying roller 65 above

50 mentioned, together with variable driving devices therefor, whereby when the match machine is in actual operation, the said mixer and roller are rotated at a normal speed to effect, respectively the intimate mixing of 55 the composition and the uniform application thereof to the ends of the depending splints on the traveling carrier, and whereby, when the machine is stopped, the said mixer and roller are rotated at a relatively

60 slow speed to continue the stirring of the composition and thus prevent its settling and thickening within the vat and upon the roller as described in Letters Patent of the United States No. 880,354, dated February 65 25, 1908.

I claim—

1. In a match machine, the combination with a splint carrier, actuating means therefor, a vessel below the path of the carrier, and a vertically-movable carrier support 70 above said vessel, of means for raising and lowering said support, pneumatic motor means including a manually-operative controlling device, and connections whereby the carrier actuating means and the support 75 raising and lowering means are simultaneously operated by said pneumatic means, so as to raise and stop the carrier instantaneously, or similarly to lower and start the carrier, thereby insuring uniform treatment 80 of the successive rows of splints with the contents of the vessel.

2. In a match machine, the combination with a splint carrier, actuating means therefor, a brake mechanism, a vessel below the 85 path of the carrier, and a vertically-movable carrier support above said vessel, of means for raising and lowering said support, pneumatic motor means including a manually-operative controlling device, and connections 90 whereby the carrier actuating means, the brake mechanism, and the support raising and lowering means are simultaneously operated by said pneumatic means, so as to raise and stop the carrier instantaneously, 95 or similarly to lower and start the carrier, thereby insuring uniform treatment of the successive rows of splints with the contents of the vessel.

3. In a match machine, the combination 100 with a main shaft, a splint carrier, actuating means between said shaft and carrier, a vessel below the path of the carrier, and a vertically-movable carrier support above said vessel, of a power-driven shaft, operative 105 connection, including locking and releasing means, between said drive shaft and the main shaft, brake mechanism for the main shaft, pneumatic motor means including a manually operative controlling device, 110 and operative connections between the said pneumatic means, the locking and releasing means, the brake mechanism and the carrier-support, whereby through proper movement 115 of the said controlling device the said locking and releasing means, brake mechanism and carrier support are simultaneously operated, thereby effecting the raising and stopping of the carrier instantaneously, or similarly the lowering and starting of the carrier, so as to insure uniform treatment of 120 the successive rows of splints with the contents of the vessel.

4. In a match machine, the combination with a main shaft, a splint carrier, actuating means between said shaft and carrier, a vessel below the path of the carrier, and a vertically-movable carrier-support above said vessel, of an auxiliary drive shaft, sprocket gearing between said drive shaft 130

and the main shaft, locking and releasing means for said gearing, brake mechanism for the main shaft, pneumatic motor means including a manually-operative controlling device, a shipper lever connected with said pneumatic means, and operative connections between said lever, the locking and releasing means, the brake mechanism, and the carrier support, whereby through proper manipulation of the said controlling device the said locking and releasing means, brake mechanism and carrier support are simultaneously operated, thereby effecting the raising and stopping of the carrier instantaneously, or similarly the lowering and starting of the carrier, so as to insure uniform treatment of the successive rows of splints with the contents of the vessel.

5. In a match machine, the combination with a main shaft, a splint carrier, actuating means between said shaft and carrier, a paraffin tank and a composition chest below said carrier, and vertically-movable carrier supports above the said tank and chest respectively, of a power driven shaft, gearing between said latter shaft and the main shaft, locking and releasing means for said gearing, brake mechanism for the main shaft, cranks, connections between said cranks and the respective carrier supports, operating rods for said cranks, and pneumatic motor means operatively connected with the said rods, the brake mechanism and the locking and releasing means, said pneumatic means including a manually-operative controlling device by manipulation of which the said

brake mechanism and the locking and releasing means are simultaneously operated, thereby effecting the raising and stopping of the carrier instantaneously, or similarly the lowering and starting of the carrier, so as to insure uniform treatment of the succeeding rows of splints with the contents of said tank and chest.

6. In a match machine, the combination with a main shaft, a splint carrier, actuating means between said shaft and carrier, a brake, a vessel beneath the path of the carrier, and a vertically-movable carrier support above said vessel, of a power driven shaft, operative connection between said latter shaft and the main shaft, said connection including a clutch element on the power-driven shaft, a shipper lever, a connection between said shipper lever and the clutch element, means connecting said lever with the carrier support, means connecting said lever with the said brake, and pneumatic motor operating means connected with said lever, said last-named means including a manually-operative controlling device by manipulation of which the said connections are operated to raise and stop the carrier instantaneously, or similarly to lower and start the carrier, thereby insuring uniform treatment of the succeeding rows of splints with the contents of the vessel.

Signed a Barberton in the county of Summit and State of Ohio this 18th day of Nov. A. D. 1915.

JOSEPH C. DONNELLY.
